UNITED STATES PATENT OFFICE

2,633,833

CARBURETOR AIR HUMIDIFIER

Clarence Schaaf, Findlay, Ohio

Application April 20, 1949, Serial No. 88,551

3 Claims. (Cl. 123—25)

1

My present invention relates to the general class of internal combustion engines or gasoline motors having water-cooling heat radiators and employed for propelling automobiles and other automotive vehicles, and more specifically to an improved carburetor air-humidifier for installation and interconnection between an air space in the upper portion of the radiator and the carburetor, or charge forming appliance of the motor. The primary purpose of the invention is the provision of an automatically operating appliance for conveying vapor-saturated air currents from the radiator, and supplying or feeding humidified air to the carburetor, which operates in conjunction with ambient conditions of temperature, humidity, and barometer pressure, and co-ordinated with the speed of the motor and forward travel of the vehicle propelled by the motor.

The appliance of my invention, which is simple in construction and operation, includes a minimum number of parts that may with facility be manufactured at low cost of production, and the parts may be assembled and installed with ease and minimum expenditure of time and labor, to assure effective performance of the functions of the humidifier.

The invention consists in certain novel combinations and arrangements of parts as will hereinafter be described in detail and more particularly pointed out in the appended claims.

In the accompanying drawings I have illustrated a complete example of a physical embodiment of my invention wherein the parts are combined and arranged in accord with one mode I have devised for the practical application of the principles of my invention.

It will however be understood that changes and alterations are contemplated and may be made in these exemplifying drawings and mechanical structures, within the scope of my claims, without departing from the principles of the invention.

Figure 1 is a view in side elevation showing a conventional automobile motor, carburetor, and reservoir, equipped with the novel humidifier of my invention.

Figure 2 is an enlarged vertical sectional view of the bowl or humidifying reservoir with its accessories.

Figure 3 is a horizontal sectional view through the structure of Fig. 2.

Figure 4 is an enlarged detail plan view of the vented radiator cap; and

Figure 5 is a vertical sectional view at line 2—2 of Fig. 4.

2

Figure 6 is an enlarged view partly in section of the angular outlet tube or elbow fitting of the radiator, showing its non-splashing vane or automatically operating flap valve; and Figure 5 is a sectional view at line 7—7 of Fig. 6.

In order that the general arrangement and utility of related parts may readily be understood I have shown in Fig. 1 a conventional internal combustion engine or motor M and its radiator R having the usual hose connections 1 and 2 to the motor, and the radiator is equipped with a removable cap 3 that is perforated as at 3a for access of air to the interior of the upper portion of the radiator casing or housing.

The motor M is equipped with a carburetor as C having an upper air intake pipe or nipple 4, and the bowl or cup 5 forming the air filter and humidifier is mounted upon the upper end of this nipple or feed pipe 4.

As best seen in Fig. 2 the cylindrical bowl 5 is provided with a centrally arranged upright annular flange 6 depending from its dished bottom 7, and an outlet pipe or air feed tube 8 having an upper beveled edge 9 around its open end, is rigidly mounted as by welding, with an enlarged skirt 10 within the flange 6. The lower end of the protruding skirt of the tube is slotted as at 11 and the slotted skirt is compressed over the nipple or pipe 4 of the carburetor by means of a clamping band or ring 12 that is secured by screw or bolt 13.

The cylindrical bowl is equipped with an inclined or dished and flanged cover or lid 14 that is detachably fastened in place with a set screw or bolt 15, and at the solid front wall of the bowl 35 facing the radiator an attaching nipple 16 is integrated with the bowl. The combined filter and humidifier is installed with its inlet nipple above the radiator, and an intake hose 17 is extended from the bowl to the radiator, to receive moistened air from the interior of the radiator.

For this purpose the radiator is equipped with an elbow fitting or angular pipe 18 to which the front end of the hose is coupled, and the angular pipe is fitted and sealed, as by welding, in an opening in the top wall of the radiator, preferably in a location remote from the perforated radiator cap.

The lower end of the elbow fitting is open to the interior of the radiator housing for ingress of moistened air, and to prevent access of splashing water from the radiator, as when an automotive vehicle is turning a corner, the depending end of the fitting is equipped with an automatically operating off-center valve for effec-

tively closing the fitting against ingress of water or drops of water.

As here shown the valve is suspended in the fitting with an upper semi-circular wing 19 adapted to swing and close the interior bore of the fitting, and this flat wing or blade has an integral depending vane 20 projecting below the lower end of the fitting, into the housing of the radiator. By means of the off-center pivot pins 21 of the valve journaled in the fitting this flap valve 10 is vertically hinged to permit free flow of moistened air to and through the fitting, as indicated by full lines in Fig. 7; and as indicated by dotted lines the flap valve cuts off ingress of splashing water to the fitting.

At the rear side of the bowl 5 its upper edge is cut away or slotted to receive a double wall air screen 22 having perforations 23, and an intermediate layer of filtering material as 24, and the slotted wall is provided with spaced angular and flanged brackets 25 that may be welded to the inner face of the wall adjoining its slot. The brackets form a holder for the curved rectangular screen or filter, and the latter may be welded or otherwise fastened securely in the brackets to seal the vented opening of the bowl.

As an emergency accessory for disposing of any excess moisture from the bowl, an outlet nipple 26 is provided in the bottom 7, and a drain hose as 27 is attached to the nipple for disposal of this excess moisture.

With the bowl mounted over the air intake opening of the carburetor, the engine suction will draw air thru the openings in the radiator cap into the upper portion or space in the radiator where the air is humidified by the vapor produced therein by the heated water and then goes thru the fitting and hose into the bowl, and from there into the carburetor where the humid air is mixed in proper proportion with the gasoline to form the explosive charge. Air is also drawn thru the opening 23 into the bowl by the engine suction whereby the proper proportion of filtered air and moist air is admitted to the carburetor.

Condensation forming within the bowl 5 is 45 drained thru the outlet nipple 26 and hose 27.

Having thus fully described my invention, what I claim as new and desire to secure by Letters Patent is:

1. In an air humidifying appliance adapted to be interconnected between the radiator having a vented cap and the carburetor of an internal combustion engine, comprising a bowl having intakes in opposite sides thereof in alignment with each other, an outlet fitting for the radiator, a hose connection between the fitting and one of said

openings, an air filtering screen for the other intake opening, a tube mounted in upright position in the bowl and having an open upper end, the tube extending thru the bottom of the bowl at its lower end and its upper end being angled and extending above the lower edge of the intakes, a drain nipple at the bottom of the bowl, and means for fastening the lower end of the tube to the carburetor air intake opening.

2. In an air humidifying appliance interconnected between the radiator having a vented cap and the carburetor of an internal combustion engine as set forth in claim 1 wherein the outlet fitting for the radiator comprises a tube bent at 15 a 90° angle with one end extending rearwardly and connected to the bowl by the hose connection, the other end extending downwardly thru the top of the radiator and communicating with the space in the upper portion of the radiator, a valve 20 within the downwardly extending tube, members carried by the valve above its horizontal center and pivotally engaging the tube whereby water splashing in the top of the radiator will close the valve so as to prevent water from entering 25 the bowl.

3. In an air humidifying appliance adapted to be interconnected between the radiator having a vented cap and the carburetor of an internal combustion engine, comprising a bowl having intakes in opposite sides thereof, an outlet fitting for the radiator, a hose connection between the fitting and one of said openings, an air filtering screen for the other intake opening, a tube mounted in upright position in the bowl having 30 an open upper end biased and in line with the openings in the opposite sides of the bowl, said tube having its lower end extending thru the bottom of the bowl and adapted to be secured to the air intake opening of the carburetor.

CLARENCE SCHAAF.
